WALKING HEEL FOR A CAST

Frank O. Wright, Memphis, Tenn.

Application November 23, 1951, Serial No. 17,493

Term of patent 14 years

(Cl. D7—5)

To all whom it may concern:

Be it known that I, Frank O. Wright, a citizen of the United States, residing at Memphis, county of Shelby, State of Tennessee, have invented a new, original, and ornamental Design for a Walking Heel for a Cast, of which the following is a specification, reference being had to the accompanying drawing, forming a part hereof.

Fig. 1 is a perspective view of a walking heel for a cast embodying my new design;

Fig. 2 is an end elevational view of the heel taken from the right of Fig. 1; and

Fig. 3 is an end elevational view thereof taken from the left of Fig. 1.

I claim:

The ornamental design for a walking heel for a cast, as shown.

FRANK O. WRIGHT.
